United States Patent Office

Des. 223,231
Patented Apr. 4, 1972

223,231

THREADED INSERT

Arthur C. Miller, P.O. Box 137,
Chester Springs, Pa. 19425

Filed Sept. 21, 1970, Ser. No. 25,083

Term of patent 14 years

Int. Cl. D8—10

U.S. Cl. D8—272

FIG. 1

FIG. 3

FIG. 2

FIG. 1 is a front view in elevation of a threaded insert showing our new design;

FIG. 2 is a top plan view thereof; and

FIG. 3 is a bottom plan view thereof.

The rear view and side elevation views are identical to the front view shown.

I claim:

The ornamental design for a threaded insert, substantially as shown and described.
